FLUID MOTOR

Application filed September 26, 1930. Serial No. 484,625.

This invention relates to improvements in fluid motors which are designed to rapidly rotate tools of any sort that may be attached to the rotor shaft, the preferable fluid being compressed air.

The object is to provide an improved means for exhausting the motive fluid from the cylinders.

In the accompanying drawing:

10 Fig. 1 is a view partly in elevation and partly in longitudinal section of a fluid motor constructed in accordance with our improved design.

15 Figs. 2, 3, 4, 5, 6 and 7 are transverse sections on the lines 2—2, 3—3, 4—4, 5—5, 6—6 and 7—7, respectively, of Fig. 1, the view in Fig. 5 showing the parts in a different working position.

20 Referring to the drawing, 1 represents a cylindrical, hollow shell having a reduced-diameter hollow hub portion 2 extending concentrically from one end to form a support for the forward bearing for the rotor shaft, there being a bearing bushing 3 inserted in the hub portion 2. The opposite end 4 of the shell 1 is open and is interiorly threaded as at 5 for a short distance in the bore 6. Various parts incident to the construction are placed in the bore 6 and are 25 therein concentrically held in alignment with the forward bearing 3, these parts being a hardened steel wear plate 7 at the forward end of the bore 6, a cylinder 8, a flat, hubbed disk 9 into which a rear bearing bushing 10 is pressed, and a threaded hose connection 11 which serves to bind the parts tightly in the shell 1.

30 The rotor body is indicated at 12 and consists of a cylindrical body portion having shaft extensions at each end, one being a comparatively long reduced-diameter extension 13, and the other a shorter extension 14, the longer extension 13 projecting beyond the bearing bushing 3 and terminating in a threaded end 13' to which tools of various sorts are to be attached, while the shorter end 14 is journaled in the bearing 10.

35 The rotor 12 revolves within, but is not in actual contact with the cylinder 8. This

cylinder 8 is constructed along the usual lines, the major portion of the exterior surface being cylindrical and adapted to closely fit the bore 6 of the shell 1, while the bore 15 of the cylinder is oblong in character as seen best in Fig. 3. By reason of the concentric disposal of the parts described the axis of rotation of the rotor coincides with the longitudinal center line of the cylinder 8, and the oblong bore 15 of the cylinder is therefore equally divided on each side of the rotor to form chambers.

40 The rotor body portion 12 is provided with a plurality of equally spaced slots 16 in which blades of the same length as the body 12 are fitted, and are adapted to slide freely in a radial direction and on rapid rotation of the rotor these blades tend to follow the contour of the oblong bore 15 of the cylinder. Referring to Fig. 5, in which the revolving parts are shown in a different working position as compared to the other views, it will be seen that the opposite blades 17, 17 are in contact with the bore 15 of the cylinder at diametrically opposite points, and that the rotor has been sufficiently rotated to show small spaces 18, 18. When a fluid under pressure is admitted to these small spaces the rotor is rotated in the direction of the arrow, the pressure being maintained behind the blades for a suitable length of time, usually terminating when the blades reach the point indicated by the character 19. The momentum of the rotor then brings other blades 20, 20 in position to receive an impulse, resulting in a very rapid rotation of the rotor.

45 Inasmuch as each blade must move inwardly and outwardly twice in each revolution of the rotor, and as the rotor revolves at very high speeds, an objectionable vibration of the motor develops during operation. The vibration may be very materially reduced by the employment of blades formed of materials such as aluminum, hard rubber, hard fiber, or bakelite. However, while blades of such light materials as were just mentioned are as certainly affected by centrifugal forces as are metallic blades of greater specific gravity, such as steel or iron,

the greater friction of the preferred bakelite blade is such that the outward movements may be comparatively sluggish with the result that, unless provision is made to prevent it, the contour of the oblong bore 15 is not closely followed, resulting in an inefficient operation due to leakage of fluid during the impulse period. Simple and effective means are described later in the specification whereby each blade is caused to have intimate contact with the cylinder bore throughout the rotation of the rotor.

The point of cut-off whereby the pressure in the spaces 18 is terminated, as well as the time of admission may be obtained in a variety of ways, the method we prefer to follow being as herewith described, it being stated at this time that although the drawing appears to show opposing flows of fluid whereby inefficient operation would result, yet by reason of the high speed of the rotor and the lag in the movements of the compressed fluid, impulse and exhaust periods occur at the desired times, this being especially true as regards the aid given in causing the blades to follow the contour of the oblong cylinder bore.

At the rearward side of each blade, referring to the direction of rotation, through the body portion of the rotor a series of passages 21 are provided, these being in a line parallel to the axis of rotation of the rotor. Each of these passages leads into an individual conduit 22 which is drilled in an eccentric, longitudinal location through the shaft extension 14 and also through the body portion 12 to a point just in advance of the foremost opening 21, Fig. 1.

The conduits 22 are equally spaced from each other and are parallel to the longitudinal axis of the rotor, and are plugged at the end of the shaft extension 14. In the shaft extension 14 a series of radial port openings 23 are drilled one for each conduit 22. In the stationary hub 9' of the disk 9 and through the stationary bearing bushing 10 a pair of diametrically opposed elongated orifices 24 are drilled which are adapted to register with the port openings 23. Air or other fluid under pressure is admitted to the chamber 25 formed in the interior of the hose connection 11 and passes through a conically formed strainer into each of the port openings 24, and then into the nearest radial port opening 23 in the shaft extension 14 and then into the passage openings 22 to the outlet ports 21 behind each blade.

Inasmuch as two ports 24 are employed and as these are diametrically opposite, it follows that in the present case where four blades are used in the rotor, the fluid may flow only to two diametrically opposed series of outlet ports 21 and thus cause an impulse to occur behind two opposite blades,

in this instance, the blades 17. The time of admission and the cut-off of the fluid to ports and passages described is governed by the size and location of the ports 24 and 23. In Fig. 5 the position is shown at the time 70 when the fluid is about to be admitted, while in Figs. 2 and 3, the position at cut-off is shown.

As the rotor continues in its rotation a preliminary exhaust port is opened, this event occurring immediately after the time of cut-off, and shortly thereafter a secondary exhaust port is uncovered, the object for the plurality of exhaust ports being for the purpose of providing ample exhaust 80 port area whereby the speed and power is increased by the elimination of possible back pressure. The preliminary exhaust is afforded by openings 26 cut in the periphery of the wear plate 7 as seen in Fig. 4. This plate closes the forward end of the cylinder 8 except at the notches mentioned, and there are provided exhaust apertures 27' in the forward wall 27 of the shell 1.

The secondary exhaust occurs when a 90 blade has passed over a series of openings 28, Figs. 1 and 3, in the cylinder 8, this series being located at a preferred point and in a path parallel to the axis of rotation and on diametrically opposite sides. These 95 openings 28 communicate with a large space 28' between the cylinder 8 and the shell 1 obtained by removing a portion of the exterior surface of the cylinder 8 as best seen in Figs. 3 and 5 and open directly at the 100 forward end into the exhaust aperture 27' in the shell 1. In Fig. 3 the blades 20 are approaching the edges 26' where the start of the preliminary exhaust is made, while in Fig. 5 the blades 20 have passed these edges 105 and exhausting of the pressure behind these blades is taking place. It will be noticed in Figs. 3 or 5 that the area of the aperture 27' for the passage of exhaust fluid is approximately equally divided as regards the quantity of fluid that may escape through the preliminary or secondary exhausts. In ordinary conditions a satisfactory speed and power may be obtained by the use of either of the methods of exhausting arrangements, 110 but by the combined arrangement the speed has been increased perhaps thirty per cent, an idle speed approaching twelve thousand revolutions per minute being attained.

At 30 and 30' are shown dowel pins, this or some other suitable arrangement being necessary to provide that the proper alignment of the stationary parts be maintained while at 31 a small pin is employed to align the bearing bushing 10 and the hub 9', since the supply ports 23 pass through these parts, the pin 31 projecting into a longitudinal slot cut in the exterior surface of the bushing 10.

Referring to Fig. 1, it will be seen that 130

the fluid at pressure in the supply ports 24 may travel by leakage in both directions along the shaft extension 14, it being impossible to secure a fluid tight joint as the bushing 10 also serves as a rear main bearing. This leakage accumulates and tends to exert a pressure on the end of the shaft 14 and on that portion of the rotor body indicated at 12', manifesting itself to the extent that 10 ordinarily the motor would not operate due to the excessive end thrust (to the right) of the rotor. Operation heretofore has been secured by supplying a ball thrust bearing at the forward end of the rotor, but we have 15 developed an arrangement whereby we not only eliminate the expensive ball thrust bearing, but also eliminate the thrust itself, by means which will now be described.

In Fig. 1, in the bearing bushing 10, a 20 small radial groove 32 is employed to relieve or vent the pressure occurring at the end of the shaft extension 14, this groove 32 communicating with a longitudinal passage 33 in the bushing, Figs. 2 and 5, which 25 in turn communicates with an annular recess 34 in the forward side of the disk 9. Part of the pressure which would accumulate on the end 12' of the rotor also leaks into the recess 34, and since this recess is 30 in communication with the exhaust passageways 28' through the medium of the radial grooves 35 in the forward side of the disk 9, the whole amount of the pressure which 35 would tend to cause end thrust is vented to atmosphere and end thrust is thereby obviated.

In motors of this type it has been the practice to admit fluid under pressure beneath the blades for the purpose of preventing 40 chattering of the blades both upon the outward and inward movement thereof. In prior constructions the fluid has been admitted to each of the blade slots directly from the passage which supplies the motive 45 fluid for the working stroke of that blade through a comparatively wide port, as a result of which, when that supply passage passes the exhaust port, the fluid will be rapidly exhausted from beneath the blade 50 and the pressure thereon relieved, allowing the blade to chatter for a portion of its inward movement. To overcome this defect, we have provided an arrangement whereby the fluid can exhaust but slowly from the 55 blade slot during the time the passage which supplies the fluid is in registry with the exhaust so that an effective fluctuating fluid pressure is maintained beneath the blade at all times. To that end we supply each blade 60 slot with fluid through a reduced orifice, and inasmuch as, due to the speed of the rotor, and the lag in the motive fluid, pressure will not at once build up to the maximum beneath the blades, we have arranged to supply 65 the fluid to the blade slot at a point in

advance of the beginning of its working stroke. To that end, instead of supplying the fluid to any one blade slot from the passage which furnishes motive fluid for that particular blade, we have arranged to supply this motive fluid from the fluid passage immediately in advance of the blade. For example, referring to Fig. 3, the inlet ports have just begun to supply motive fluid to the passages 21 to drive the blades 17 which are just starting on their working stroke and it will be noticed that reduced orifices 36 lead from the conduits 22 to the bottom of the slots beneath the blades 20 which are just about to begin to move into the slots. Pressure will begin to build up beneath the blades 20 until by the time they have reached the position of the blades 17 in this figure, a maximum pressure will exist. As soon as the blades 17 have passed the exhaust ports however a reduction in pressure is had in those supply passages which have supplied the slots of the blades 20, but, due to the fact that the fluid beneath the blades can escape but slowly through the reduced orifices by reason of leakage by the blades, a fluid cushion is maintained beneath the blades 20 not only through their entire working stroke but also during the entire inward movement in the slots.

A conical strainer 37 formed of perforated sheet metal is employed to prevent ingress of foreign matter into the motor proper. This strainer may be a one-piece rolled member or pressed and formed from the flat; in either event, the larger end is forced into an annular recess 37 in the rear of the disk 9, while the smaller end is forced over the hub 9' and crimped into a recess 38 in the outer surface thereof.

Lubrication of the rotative parts is accomplished by feeding a small amount of lubricant into the motor from a container (not shown), the lubricant being carried by the fluid medium. Heretofore, the forward main bearing has received but scanty lubricant due to its position and the fact that the lubricant was carried in the fluid stream, resulting in rapid wear or shut-downs to lubricate this bearing. By simple arrangements we are enabled to afford ample lubrication for this bearing, one of the means being a plurality of openings leading from the exterior of the extended hub 2, a single opening 39 on each side of the hub being shown in Fig. 7. These holes are located in the path of the escaping motive fluid which tends to expand immediately on leaving the apertures 26, and a portion of the fluid stream therefore flows forwardly along the hub 2, with the result that a minute quantity of lubricant is being continuously deposited in the openings 39 and is carried therethrough into a circumferential groove 40 in the surface of the bushing 3. The lub-

ricant then finds its way into the oil grooves 41 in the interior of the bushing 3 through openings 42 leading from the circumferential groove 40.

5 Another method of lubricating the rear end of the forward main bearing is by the radial grooves 44 which are provided in the rearward side of the wear plate 7, Figs. 4 and 7. These grooves are small half-round 10 grooves leading from those portions of the wear plate which are exposed to the pressure of the fluid, as best seen in Fig. 3, so that during each impulse, a small portion of lubricant is deposited therein and forced by 15 the pressure into an annular space 45 directly at the rear of the bushing 3. The rotation of the shaft coupled with the effects of the fluid pressure readily cause the oil to work its way into the bearing bushing 3.

20 Having thus described our invention, we claim:

1. In a fluid motor, a casing, a cylinder in said casing, a rotor in said cylinder, an elongated exhaust port in an end of said 25 casing leading directly from the interior of said cylinder in an axial direction, an exhaust passage between said cylinder and casing communicating with said port, said exhaust passage extending throughout the major portion of the length of said cylinder, said cylinder having at least one exhaust opening leading to said passage.

2. In a fluid motor for a cutting tool, a cylinder, a rotor in said cylinder, an exhaust 35 port at the tool end of the cylinder leading directly from the interior thereof in an axial direction, a longitudinal exhaust passage in the wall of the cylinder leading to said exhaust port and said cylinder having at least 40 one exhaust opening leading to said passage, said exhaust passage extending throughout the major portion of the length of the cylinder.

In testimony whereof, we have hereunto 45 set our hands this 19th day of September, 1930.

WALTER T. HAMILTON.
GROVER F. ILGEN.
